UNITED STATES PATENT OFFICE.

JOHN D. ARNOLD, OF MURRAY, ASSIGNOR OF TWO-THIRDS HIS RIGHT TO
WILLIAM E. NEER AND BYRON D. BIDDLECOM, OF ROCHESTER, N. Y.

IMPROVEMENT IN HUBS FOR CARRIAGE-WHEELS.

Specification forming part of Letters Patent No. 131,838, dated October 1, 1872.

To all whom it may concern:

Be it known that I, JOHN D. ARNOLD, of Murray, in the county of Orleans and State of New York, have invented a new and useful Improvement in Metal-Hubs for Carriage-Wheels; and I do hereby declare that the following is an exact and full description thereof, reference being had to the accompanying drawing and to the letters of reference marked thereon.

The drawing represents a central longitudinal section of my cast-metal hub.

In the accompanying drawing, A B denote the two principal parts of which the hub consists, and C D refer to the two annular disks between which the spokes of the wheel will be inserted.

The shell B, which constitutes the inner end of the hub, is cast with the axle-box E; and the shell A, which constitutes the outer end or half of the hub, is cast with the rim F and annular support G, into which the box E fits closely. The chambers H and I extend entirely around the box E, as indicated in the drawing. The outer end of the box E will be provided with a screw-thread, as will also the support G, which will serve to retain the parts firmly together. The annular disks may be made with flutings or corrugations, either radially or in circles, upon their inner faces, to impinge upon and clamp the tenons of the spokes, which will be inserted between them. To insert the spokes three blocks may be first inserted between the disks at equal distances

apart, and after three spokes are driven between the flanges C D, the three blocks may be removed and the remaining spokes will be driven, filling up the spaces. After all the spokes are inserted the part A of the hub, which serves, with its support G, as a nut, will be screwed up to clamp the spokes between the flanges C D.

A carriage-wheel constructed with my improved hub will present the ordinary appearance, when painted, of the wheels constructed with the wooden hub; and its weight will not be much greater. It also has the advantage of superior strength and durability. By the use of my hub new spokes for repairs may be inserted by unscrewing the part A and inserting the spoke, and then screwing up the part A, and thereby clamping the disk C with the spokes, as in the first instance. This may be done without cutting and resetting the tire of the wheel.

Having described my invention, I claim, and desire to secure by Letters Patent—

The combined metal hub and box, constructed of the four parts A, C, D, and B E, connected and arranged to operate conjointly, in the manner and for the purpose substantially as described.

In testimony hereof I have hereunto set my hand this 19th day of August, A. D. 1871.

JOHN D. ARNOLD.
